PIPE CLEANER

Florian Possinger, Ebenezer, N. Y.

Application November 27, 1934, Serial No. 755,008

2 Claims. (Cl. 131—13)

My invention relates to improvements in pipe cleaners, and more particularly to a cleaner of the reamer type adapted for cleaning or reaming out the bowl of a tobacco pipe.

5 The invention has for its primary object the provision of a cleaner or reamer which is self-adjustable to the varying interior contour of bowls of tobacco pipes of various shapes and sizes.

10 Another object of my invention is to provide a simple and inexpensive cleaner of this type which will effectively free the walls of pipe bowls of tobacco and carbon, and which will as effectively clean the bottom of the bowl as the side wall thereof.

15 A further object of my invention is the provision of a cleaner of this type, comprising few parts which are capable of being readily assembled and connected together without the use of rivets, solder, or other extraneous fastening means.

20 A still further object of my invention is the provision of a cleaner or reamer for pipe bowls having a substantially U-shaped reaming element constructed of a comparatively thin narrow resilient strip of metal having a suitable handle attached to its outer or free ends and being stiffened adjacent said handle to resist the torsional strain applied thereto while rotating the same 25 during the act of cleaning a pipe bowl.

25 The invention consists in the novel features of construction, and in the arrangement and combination of parts to be hereinafter described and more particularly pointed out in the subjoined 30 claims.

35 In the drawing:

Fig. 1 is a side elevation of my invention applied to the bowl of a tobacco pipe showing the manner in which the cleaner or reamer is manipulated.

40 Fig. 2 is a longitudinal section through the bowl-end of the pipe showing my improved cleaner or reamer inserted therein and the manner in which it is rendered self-conformable to the interior contour of the pipe bowl.

45 Fig. 3 is a perspective view of the complete cleaner or reamer.

Fig. 4 is a section taken on line 4—4, Fig. 2.

Fig. 5 is a longitudinal section through the 50 handle or outer end of the device.

Fig. 6 is a cross section taken on line 6—6, Fig. 5, looking in the direction of the arrow crossing said line.

Fig. 7 is a detached perspective view of the 55 sleeve retainer forming part of the handle.

Referring to the drawing in detail, 8 designates a tobacco pipe having a tobacco bowl 9 at one end, as is common.

The cleaner or reamer comprises three parts, 5 namely, a cleaning or reaming element 10, a handle 11, and a retainer sleeve 12 forming part of said handle. The cleaning or reaming element is formed of a narrow strip of flat resilient metal, such as shock-spring or highly carbonized steel, properly tempered and curved between its ends 10 to provide a yielding bight 13 and yielding side parts or legs 14.

The handle 11 is thimble-like in form to provide a peripheral wall 15, preferably cylindrical, and an outer end wall 16. The outer surface of 15 this handle is serrated or otherwise roughened, as at 17, to aid in gripping the same between the thumb and forefinger of a hand, or in any other manner.

The retainer sleeve is provided at diametrically 20 opposite points with grooves 18 which extend the full length thereof, and may be a trifle less in depth than the thickness of the flexible strip material forming the cleaning or reaming element. The outer or free ends of the cleaning or reaming 25 element are placed within the grooves and the sleeve inserted into the handle under pressure, with the result that the ends of the substantially U-shaped cleaning or reaming element are firmly clamped between the thimble-like outer and the 30 sleeve-like inner members of the handle. The three parts of the device are thus firmly connected together without resorting to the use of rivets, solder, or other fastening means.

35 It will therefore be apparent that the forcing of the retainer sleeve into the thimble-like handle assures a secure fastening of the cleaning or reaming element in place, and due to the fact that the retainer sleeve is inserted into the thimble-like handle under considerable pressure, 40 the grooves within said retainer sleeve need not necessarily be shallower than the thickness of the metallic strip forming the cleaning or reaming element. However, to assure a secure fastening, the strip should at least correspond in thickness to the depth of said grooves. When thus assembled the device comprises a loop-like or substantially U-shaped cleaning or reaming element and a handle, which latter, in a broad sense, may be considered to include both members 45 11 and 12, herein separately referred to as the handle and retainer sleeve, respectively. The loop of the cleaning or reaming element has its greatest width between its bight and the handle, and is therefore rendered quite resilient so as 50 55

to conform to the interiors of various sized bowls of tobacco pipes. This formation permits of the ready insertion of the cleaning or reaming element into a bowl, and by pressing downwardly 5 upon the device, said element automatically shapes itself to the interior contour of the bowl so as to ream the same from the bottom to the top; or at least, depending on the depth of the bowl, from the extreme bottom upwardly or outwardly toward the top.

When inserted into the bowl the handle is taken hold of and rotated, with the result that the flexible cleaning element is moved circularly in contact with the inner wall surface of the 15 bowl, the sharp corners at the edge of the element acting upon the adhering tobacco or carbon and effectively scraping or reaming the same from the wall of the bowl.

The cleaning or reaming element may be rotated continuously in a circular direction, or back and forth, as may be found desirable, and in such cases where the element is not in contact with the upper portion of the wall of the bowl when fully inserted into the bowl, after reaming the 25 lower or inner portion, the device may be lifted or raised so that the cleaning of the upper portion of the wall can take place.

Such rotary movement of the cleaning or reaming element results in torsional strain being applied to the side parts or legs thereof, particularly in proximity to the handle, and since said element is most effective when made comparatively thin due to the desirability of having it conform itself to the shape of the bowl, I provide each 30 of the side parts or legs 14 of the element adjacent the handle with stiffening ribs 19 which extend downwardly from the handle and from opposite ends are gradually widened to a point midlength so that they gradually merge from 35 their medial points directly into the flat formation of said parts or legs. By thus stiffening the spaced parts or legs of the cleaning or reaming element all tendency of said parts or legs to twist adjacent the handle is obviated.

It will be apparent therefore that I have produced a pipe cleaner or reamer which is exceedingly flexible so that it will conform itself to the shape of the interior of a tobacco bowl when inserted thereinto, yet be exceedingly rigid, and in addition thereto provide a convenient handle having an outer end face formed by the outer end wall 16 of the handle, which can be used as a tamper for pressing down the tobacco in the bowl while smoking. The device is therefore one 10 which will serve as a pocket companion to a tobacco pipe, and will aid in keeping a pipe in perfect smoking condition and also enable the tobacco to be properly packed during the act of smoking without resorting to the usual method 15 of inserting a finger into the bowl for this purpose, which occasionally results in pain due to a slight burn, and also causes soiling of the hand.

Having thus described my invention, what I claim is:

1. A tobacco pipe cleaner, comprising a hollow handle, a thin flat resilient strip of metal curved between its ends and having its ends inserted into said hollow handle, and a retainer sleeve provided with grooves at diametrically opposite ends 25 to receive the ends of said strip, said retainer sleeve being forcibly inserted into said hollow handle to clamp the ends of said strip between said handle and said retainer sleeve.

2. A tobacco pipe cleaner, comprising a cylindrical handle, a sleeve forcibly inserted into said handle and having grooves arranged longitudinally therein at diametrically opposite points, and a flat resilient strip of metal curved between its ends and having its ends inserted into said 30 grooves and clamped between said handle and said retainer sleeve, said strip having stiffening ribs near its ends extending downwardly from said handle, each of said ribs being gradually widened from its ends towards its longitudinal 35 center so that said ribs gradually merge at opposite ends into the flat portions of said strips.

FLORIAN POSSINGER.
